(57) **CLAIM**

The ornamental design for a weighted vest, as shown and described.

DESCRIPTION

FIG. 1 is a perspective view of a weighted vest according to a first embodiment;

FIG. 2 is a front view of the weighted vest of FIG. 1;

FIG. 3 is a rear view of the weighted vest of FIG. 1 laid flat so that side panels of the weighted vest are visible;

FIG. 4 is a left side view of the weighted vest of FIG. 1;

FIG. 5 is a right side view of the weighted vest of FIG. 1;

FIG. 6 is a top view of the weighted vest of FIG. 1; and,

FIG. 7 is a bottom view of the weighted vest of FIG. 1. The broken lines in the drawings depict stitching and form no part of the claimed design.
